Primary Examiner—Doris V. Coles*Assistant Examiner*—Elizabeth A. Albert(74) *Attorney, Agent, or Firm*—Michael Zall(57) **CLAIM**

I claim the ornamental design for a security pass, as shown and described.

DESCRIPTION

FIG. 1 is a front perspective view of a security pass showing my new design;

FIG. 2 is a front view of the security pass shown in FIG. 1; FIG. 3 is a rear view of the security pass shown in FIG. 1; FIG. 4 is a top end view of the security pass shown in FIG. 1;

FIG. 5 is a bottom end view of the security pass shown in FIG. 1;

FIG. 6 is a left side view of the security pass shown in FIG. 1; the right side view a being a mirror image thereof; and, FIG. 7 is a cross-sectional view of the security pass in use on, for example, a shirt pocket.

The broken lines showing environment in the drawings are for illustrative purposes only and form no part of the claimed design.
